BASE FOR A BOWLING BALL CARRIER OR THE LIKE

Simon Javkin, 160 West End Ave.,
New York, N.Y. 10023

Filed Apr. 17, 1972, Ser. No. 245,002

Term of patent 14 years

Int. Cl. D3—02

U.S. Cl. D87—5 D

FIG. 1

FIG. 2

FIG. 3

FIG. 4

FIG. 1 is a top plan view of a base for a bowling ball carrier or the like embodying my new design;

FIG. 2 is a bottom plan view thereof;

FIG. 3 is an enlarged side elevational view thereof, the opposite side being identical; and

FIG. 4 is a sectional view taken along the line 4—4 of FIG. 1 on an enlarged scale but on a scale smaller than FIG. 3.

I claim:

The ornamental design for a base for a bowling ball carrier or the like, as shown.
